UNITED STATES PATENT OFFICE.

BÉLA ZSARNAY, OF NEWARK, NEW JERSEY, ASSIGNOR OF ONE-FOURTH TO WILLIAM FAY AND ONE-FOURTH TO JOHN BISCHOFF, BOTH OF NEWARK, NEW JERSEY.

AEROPLANE.

1,325,920.

Specification of Letters Patent. Patented Dec. 23, 1919.

Application filed July 2, 1917, Serial No. 178,061. Renewed November 8, 1919. Serial No. 336,736.

To all whom it may concern:

Be it known that I, BÉLA ZSARNAY, a subject of the King of Hungary, resident of Newark, county of Essex, and State of New Jersey, have invented certain new and useful Improvements in Aeroplanes, of which the following is a specification.

This invention relates to improvements in flying machines and has as its principal object 10 the provision of a machine which combines the operative principle of a balloon with a "heavier than air" machine, together with helicopters, and a plurality of fixed horizontal plates or planes. 15 A further object is in the provision of a car which is capable of carrying a relatively large number of passengers, or such weight as may be desired, two independently actuated motors being employed for the rotation 20 of the propellers, and finally, to provide a machine with a safety landing device, the various planes, propellers and landing device being assisted by an air blast, the current for which is obtained from the motors. 25 These and other like objects, as extreme buoyancy, and the ability for long and continued service, are attained by the novel design, construction and combination of parts hereafter described and shown in the accompanying drawings, forming a material 30 part of this disclosure, and in which,—

Figure 1 is a top plan view of a flying machine made in accordance with the invention.

Fig. 2 is a side elevational view of the same.

Fig. 3 is an end view thereof.

Fig. 4 is an enlarged vertical sectional view taken substantially on the center line of the car, and

Fig. 5 is a side elevational view of one of the air dispensing nozzles.

In carrying out the invention, a balloon 10 is provided capable of being filled with gas, so as to give buoyancy to the apparatus, 45 and encircled by frame bands 14, having stirrups 13 engaging a car 15, provided with windows 16 and a central door 17, through which passengers may enter or leave.

Extending supports 18, secured to the 50 stirrups 13, pass below the car and have attached at their lower ends, pairs of landing wheels 19, the same being preferably of a pneumatic type, so as to cushion the descent or landing movement of the car.

Arranged in the car near the ends thereof, 55 are the power elements consisting of a pair of motors 20, so that should one be disabled the other can be used, the motors being preferably of the internal combustion type, and a supply of fuel is carried by the apparatus in suitable reservoirs.

Operated by the motors are air compressors 21, by means of which the air tanks 22 are filled with air at a high pressure.

A series of arcuate planes 25 are disposed 65 upon each side of the balloon 10, other planes 26, acting in the manner of rudders being arranged at the rear of the balloon. Angularly disposed supports 28 extend out laterally from the balloon carrying rotatably 70 mounted propellers 29, the same being arranged vertically in the manner of a helicopter, so that when actuated as to cause the machine to ascend, the propellers 29 being driven by the motors 20 through flexible shafts 31, while at the ends of the balloon frame are other propellers 33, driven by the shafts 34, which are also operated by the motors.

Arranged below the planes 25 are nozzles 37, on the pipes 38, communicating with the compressors, 22, other pipes 39 leading from each of the compressors to similar nozzles upon the opposite side of the balloon. Other pipes 40 lead from the compressors to a point below the propellers 29, and still other pipes 41 lead to nozzles 42 directed against the end propellers 33 which are further impelled by nozzles 44 supplied by air through the pipes 45, whereby their action 90 is greatly facilitated and also the steering of the machine is substantially aided.

Should either compressor become disabled pipes 46 connect between the compressors and pipes 41, all of the several pipes being 95 controlled by valves as shown.

Centrally below the car is suspended a concave, cup-like element 48, through which enters pipes 49 from the compressed air tanks, the pipes communicating with nozzles 50 whereby a draft of air directed downward and at an angle, the same forming in effect a cushion against the landing of the apparatus prior to contact of the wheels with the ground, and also assisting materially in 105 the initial rising movement into the air.

Openings 52 and 54 are provided in the balloon, the former being used to exhaust

the air and the latter in filling the balloon with hydrogen, both openings being provided with suitable valves.

In operation, the passengers having entered through the door 17 and arranged themselves within the car 15, the motors are started, compressing the air within the tanks 22, whereupon the inlets to the nozzles 44 are opened and the propellers 29, caused to rotate, raising the machine from the ground to any desired extent, longitudinal movement of the car being effected by the end propellers 33 so that the apparatus may be moved in either direction.

From the foregoing it will be seen that the various air currents are taken from the atmosphere and delivered to the compressors 22, for which they are delivered under the immediate control of the parties within the car, also that the motors and steering means employed are readily accessible, and that the power leading through the several pipes or tubes can be regulated according to the position of the valves, thereby furnishing means for steering and balancing as well as the raising of the airship, which, as will readily be seen, is a complete combination of aeroplane and balloon, which may be caused to ascend in an expeditious manner or to land without danger to the car structure or its occupant.

Having thus described my invention, what I claim as new and desire to secure by Letters Patent, is:—

1. In a flying machine, the combination

with a balloon, a pair of helicopters arranged at the sides thereof, and a pair of propellers, one arranged at each end of said balloon, of a car supported by said balloon, means for the entrance and exit of parties 40 therefrom, air compressors within said car, a plurality of vanes attached alongside said balloon, means for directing air jets against said vanes, horizontal rudders at the rear of said balloon, means for directing a current 45 of air against said helicopters, a concave-convex element below said car, means for directing one or more currents of air therein, said currents of air acting as a cushion against the landing of said car, and means 50 for actuating all of said propellers.

2. In a flying machine, the combination with a buoyant element adapted to be inflated, a car suspended therefrom, vertically operable propellers mounted upon opposite 55 sides of said buoyant element, said propellers working in a horizontal plane, a propeller at each end of said buoyant element operating in a vertical plane, a source of power carried by said car, a series of laterally extending vanes attached to said buoyant element at the center thereof, means for producing a current of air against said vanes, a pair of horizontal rudders at the rear of said buoyant element, an inverted cup carried below said car, and means for producing a cushioning current of air in said cup.

In testimony whereof I have affixed my signature.

BÉLA ZSARNAY.
